UNITED STATES PATENT OFFICE.

BURTON S. AIKMAN, OF CHICAGO, ILLINOIS, ASSIGNOR TO NATIONAL BRAKE & ELECTRIC CO., OF MILWAUKEE, WISCONSIN, A CORPORATION OF WISCONSIN.

ENGINEER'S VALVE.

1,065,650.

Specification of Letters Patent. Patented June 24, 1913.

Application filed August 1, 1910. Serial No. 574,773.

To all whom it may concern:

Be it known that I, BURTON S. AIKMAN, a citizen of the United States, residing at Chicago, in the county of Cook and State 5 of Illinois, have invented a certain new and useful Improvement in Engineers' Valves, of which the following is a full, clear, concise, and exact description, reference being had to the accompanying drawings, forming 10 a part of this specification.

My invention relates to manually controlled valves and is particularly concerned with that type of valve which is used in connection with the braking system of a 15 street car or railroad train. As is well known, these valves, commonly called engineers' valves, are employed in both "straight air" and "automatic" braking systems. While the valve of my invention 20 may be adapted to the automatic system, its most practical and advantageous use and the use which I particularly intend it for is in connection with the straight air arrangement. In straight air systems it is common 25 to provide a valve which connects with a reservoir storing compressed air, with the brake cylinder and with the atmosphere, mechanism being provided to connect the brake cylinder either with the reservoir or 30 with the exhaust.

Broadly the object of my invention is to secure improved operation in a simplified device, and to this end I propose various 35 novel features all of which will be described in detail.

It is a fact that it is desirable to control the passage of the effective fluid to a nice degree, that is, to graduate the rush of air so that the motorman or engineer may 40 control the brakes on his car or train to just the extent that the circumstances require. This feature of graduating the passage of the air is often termed "wire drawing" the air and it is advantageous not only in applying the 45 brakes, when under ordinary circumstances it is desirable to bring the car or train to a stop gradually, but also in releasing the brakes where often it is desirable to bring the car or train to a stop gradually and 50 also in releasing the brakes where often it is desirable to keep the motion of the car or train retarded without entirely stopping it. It has been found, however, that valves which secure this graduating feature can- 55 not be relied upon to absolutely shut off the

passage of air when that action is desirable, and in my copending application, Serial No. 547,888, filed March 7, 1910, I disclose a structure which includes two valve elements, one adapted to absolutely shut off the passage of air, and the other adapted to graduate the current. 60

My present invention comprises a single valve element for performing both functions, that of "wire drawing" the air being 65 secured in an improved manner. Considering the graduating feature alone it is important in my invention that it is secured by means of a sliding or piston valve, and, as will more fully appear in the detailed arrangement as considered, it is this construction which warrants terming my device a "self-cleaning valve." One of the difficulties which has been experienced in arrangements of this kind is that of the collection 70 of scales from the inside of the pipes of the system at the seat of the usual lift valve, this valve being the type employed since it is the most efficient so far as absolutely shutting off the rush of air is concerned. When, 75 in a valve of this type, the valve member is lifted from its seat slightly, there is immediately a considerable rush of air since the annular passage at once afforded aggregates to a considerable area. For solid particles, however, the situation is different and the scales carried by the air from the pipes of the system collect upon the valve seat and seriously impair the operation of the device. By my invention, however, this 80 difficulty is entirely obviated and the rush of air is relied upon to keep the valve seat clean and free from these solid particles. I secure this desirable feature by an arrangement wherein the lift valve is opened to a 85 considerable extent before the graduating valve is opened, and since the difficulty of collecting scales is not encountered in the use of sliding valves because the passage for solid particles is about the same as that for 90 a fluid, the scales will rush into and meet with a large passage when they get to the seat of the lift valve and may easily be carried through it and beyond into the brake cylinder or the exhaust where they can do 95 no harm. 100

Another important feature of my invention is that the usual chamber below the bonnet is not necessarily an air chamber, and the use of a gasket between the relatively 110

movable parts, a very undesirable feature, is therefore entirely avoided. To confine the air to the channels as distinguished from the bonnet chamber, which two elements would 5 otherwise be connected by the openings in which the valve stems operate, I provide a stuffing element in the way of a compressible ring, preferably lead, between the members of a two part valve stem so that when the 10 valve is opened, the time when stuffing is needed, the lead ring will be compressed transversely and expanded radially to secure the desired result. It is also desirable that the valves be given a straight line 15 movement, and to this end I provide an improved arrangement in the way of a rack and pinion mechanism which is not only operative effectively, but is of simple construction as well. The manner in which the 20 valve members are placed so as to secure easy operation is a further feature of my invention.

My invention is embodied in the device illustrated in the accompanying drawings, 25 in which—

Figure 1 is a front elevational view of the device; Fig. 2 is a side elevational view thereof; Fig. 3 is a view similar to Fig. 1, except that the central part of the structure 30 is shown in diametrical section; Fig. 4 is a horizontal sectional view taken on the plane of the line 4—4 of Fig. 3; Fig. 5 is an isolated view of several of the parts, being approximately a section taken on the 35 line 5—5 of Fig. 3; Fig. 6 is a cross-sectional view taken on the plane of the line 6—6 of Fig. 3; Fig. 7 is a side elevational view of the sleeve in which the piston valve operates; Fig. 8 is a cross-sectional view 40 taken on the plane of the line 8—8 of Fig. 7; Fig. 9 is an isolated view of part of the two valve stem members, showing the stuffing ring therebetween, and Fig. 10 is an elevational view of the stuffing ring.

Like reference numerals are applied to the 45 same parts throughout the various figures.

The main casing is illustrated at 11, having eye lugs 11^a, 11^a, so that it may be secured in any desired position, and, as best 50 shown in Figs. 3 and 4 is provided with two diametrically opposite circular sockets, which provide for the valve chambers and which are closed by means of the screw caps 12, 12. One of these sockets is supplemented 55 by a circular chamber 13, best shown in Fig. 6, while the other is supplemented by a similar chamber 14. The socket associated with the chamber 13 is connected with a substantially concentric chamber 15 by means of an 60 opening 16, in which a bushing 17, which forms a valve seat, is disposed. The other socket is connected with a substantially concentric chamber 18 by means of a similar opening 16 in which a similar bushing 17 65 is disposed to form a valve seat. In each of

the sockets a sleeve 19 is fitted, this sleeve being shown in detail in Figs. 7 and 8. It will be seen that the openings 20, 20 therein lead into either the chamber 13 or the chamber 14, as the case may be. The walls which close the chambers 15 and 18 are each provided with a bore in axial alinement with the sleeves 19 in which bore a bushing 21 is fitted and it is in these bushings that the two part valve stems 22, 22 are disposed to operate. The construction of these valve stems will be referred to later in detail. The valve stem associated with the chambers 13 and 15 is provided with a reduced end which screws into the valve member 23, while the valve stem which is associated with the chambers 14 and 18 is provided with a reduced end which screws into the valve member 24, these valve members operating as pistons in the sleeves 19, 19, as clearly shown in Figs. 80 3 and 4. Each of these valves is provided with a layer 25 of compressible seating material and is held against the bushing 17 by means of the helical spring 26 disposed between the valve member and a pocket 27 85 in the associated cap 12. It will be seen from the drawings that the openings 20, 20 in the sleeves 19, 19 are so disposed longitudinally that they are closed by the valve members 23 and 24 when these valve members are seated upon the bushings 17, 17. It is further clear from the drawings that either of the valve members can be lifted 90 from its seat to a considerable extent before the openings 20, 20 are opened, this being the feature which secures the self-cleaning 95 of the valve, hereinbefore referred to, which will be taken up more in detail hereinafter.

The casing 11 is provided with the pipe 105 studs 28 and 29, the former being adapted to be connected by means of piping 30 and coupling 31 with the brake cylinder and the latter being adapted to be connected with the reservoir by means of the pipe 32 and 110 coupling 33. The pipe 28 is connected with the chamber 13 by means of the channel 34 and with the chamber 18 by means of the channel 35. The pipe 29 is connected with the chamber 14 by means of the channel 36. 115 The chamber 15 is connected, by means of the channel 37 with the exhaust pipe 38.

The central chamber 39, which may conveniently be termed the "action chamber" 120 is closed by means of the bonnet 40, a gasket 40^a intervening, held in place by means of the bolts 39^b. This bonnet has a central bore in which a bushing 41 is disposed, this bushing forming the channel for the spindle 42, the upper end of which is formed for the reception of a handle 43, and is protected by a cap 44, which incidentally is provided with notches 45 on the disk portion thereof for coöperation with the spring pressed pin 46 in the handle 43, this being a convenient 130

arrangement for determining the stopping points of the handle. The spindle 42 is set in the bonnet 40 in some suitable manner, and at its lower end is provided with a pinion member 47, best shown in Fig. 5, the teeth of which mesh with the teeth 48, 48, forming a rack upon the inside of one of the upwardly extending members of the channel piece 49, this channel piece being set upon the depending guides 50, 50, preferably integral with the bonnet 40. These guides are formed so that they may extend into the chamber 39, as shown in Fig. 3, and provide for the guidance of the channel piece 49 in its side to side reciprocation, as will be pointed out. The movement of the valve spindle in the direction of the arrow A, Fig. 5, will secure the movement of the channel piece 49 to the right, while movement of the spindle in the opposite direction will result in the movement of the channel piece to the left. The channel piece is provided on its under side with a depending lug 51 which is in alinement with the protruding ends 25 of the valve stems 22, 22, as shown in Fig. 5. The lug 51 merely abuts against one valve stem or the other, depending upon the direction in which the spindle is turned, and it is evident that such movement will 30 result in corresponding movement of that particular valve stem. It will be noted that the valve stems are in two parts, as best illustrated in Fig. 9, and between these parts a ring 52, of lead or some other suitable 35 material, is disposed. It will be noted that the adjacent ends of the stem members are slightly conical and that the cross-section of the ring 52 is conformed in this respect. When the spindle 42 is turned, say, to the 40 right, the channel piece 49 will move to the right, and the motion will be transmitted to the valve 24, this action compressing the associated lead ring 52 transversely so as to expand it radially to take up wear and 45 to cause a packing in the bushing 21. The utility of this arrangement will hereafter appear. The spindle 42 is provided with a central partial bore at its lower end in which a pin 53 is disposed, this pin having 50 a conical point adapted to rest in one of the pockets 54, 54. A spring 55 may be provided to hold the pin 53 in one of the pockets more or less obstinately. This arrangement provides for locking the channel piece against 55 the action of the springs 26.

It will be seen that the valve 23 controls the connection between the chamber 15 and 13 and consequently between the brake cylinder and the exhaust, while the valve 24 60 controls the connection between the chambers 14 and 18 and consequently between the reservoir and the brake cylinder. As best shown in Fig. 3, each of the sleeves 19 is provided with a notch 55^a which connects 65 with the equalizing passage 56 extending

from the sleeve and communicating with the inside of said sleeve at the back of the valve. The notch 55^a provides for connection between the equalizing passage and the chamber 15 or 18, whichever the case may be. 70 The utility of this arrangement will be set forth hereinafter.

The operation of my device is as follows: As before stated, the pipe 30 leads to the brake cylinder, and it is evident that when 75 the brakes are to be set this pipe must be connected with the reservoir, and when the brakes are to be released it must be connected with the exhaust. Thus the pipe 30 connects with the chambers 13 and 18, the 80 passage to the exhaust being controlled by the valve 23, and the connection with the reservoir being controlled by the valve 24. By reference to Fig. 3, it will be seen that the valves 23 and 24 are of such thickness 85 and are so disposed that, while they substantially close the openings 20, 20, in the sleeve, there is an opportunity for leakage between the chamber 13 or the chamber 14, whichever the case may be, to the space in 90 back of the valve. When it is desired to open either of the valves, the initial opening movement operates against this back pressure so that a positive and not merely an incidental movement of the handle is 95 necessary to open the valve. As soon as the valve has been opened, however slightly, the air collected in the back of the valve may rush through the equalizing passage 56, through the notch 55^a, and into the chamber 100 15 or 18, whichever the case may be. This balances the valve, and the further movement thereof is free and easy. These equalizing passages and leakages are, of course, so restricted as to be insignificant when the 105 main rush of air is considered. When it is desired to set the brakes, the handle is turned toward the right, thus rotating the opening member 47 in the direction of the arrow A and consequently moving the channel piece 49 toward the right (Fig. 3). The lug 51 on the channel piece then abuts against the stem 22 of the valve 24, and, before opening the valve, compresses the 110 lead ring 52 to take up wear and prevent any leakage from the chamber 18, between the bushing 21 and the stem 22, into the chamber beneath the bonnet 40. It will be noted that the valve 24 is lifted from the seat 17 a considerable distance before the 115 apertures 20, 20 are open. The engagement of the valve 24 on the seat 17 positively prevents the passage of the air, and it is evident that after the valve has thus been lifted, the passage of the fluid is controlled 120 alone at the openings 20, 20. The sliding valve action graduates the passage of the air and the apertures 20, 20, are elongated so that the graduation may be all the more effective. As before pointed out, the scales 130

which might be picked up from the system tubes will not collect at the seat of such a sliding valve and after once passing that valve, it is clear that their passage will not be interfered with by the lift valve arrangement. This is, of course, desirable since it enables the engineer or motorman to apply the brakes gradually, it being clear that he may throw the valve wide open instantly in the case of an emergency. In again returning the handle to the normal position, the valve reseats upon the bushing 17 to positively prevent the flow of air. In the further movement of the handle to the left as when the motorman or engineer desires to release the brakes, the same valve action, as has been described relative to the valve 24, takes place at the valve 23. Since this effective graduation is here also possible, the motorman or engineer is enabled to release the brakes very slightly, should he so desire, as in the case where the wheels of the car or train should be kept retarded but not stopped. Here also the valve is effectively balanced after it is once opened and here also the motorman or engineer can throw the valve wide open immediately to secure a sudden release. The graduating features are advantageous also in that there is a great saving of air.

I claim as new and desire to secure by Letters Patent:

1. In an engineer's valve, a casing having a socket, a sleeve fitting in said casing, an air chamber at one end of said sleeve, an air chamber around part of the periphery of said sleeve, said sleeve having peripheral openings leading into the latter air chamber, a piston sliding in said sleeve, and a valve seat at the end of said cylinder near said first-named chamber, said piston being arranged to seat upon said valve seat and to slide past the openings in said sleeve.

2. In an engineer's valve, a casing, guides carried by said casing, a channel piece reciprocating in said guides, a stem mounted in the casing, a pinion mounted on said stem engaging with teeth on said channel piece, a valve, and mechanical connection between said valve and said channel piece.

3. In an engineer's valve, a casing, guides carried by said casing, a channel piece reciprocating in said guides, a stem mounted in the casing, a pinion mounted on said stem engaging with teeth on said channel piece, a valve, and a stem extending from said valve and arranged for engagement by said channel piece.

4. In an engineer's valve, an air chamber, an action chamber, a valve controlling the passage of air to and from said air chamber, a valve stem extending from said air chamber to said action chamber, said valve stem being in two parts, and a compressible member between the parts of said valve stem for

forming a packing in the stem journal when longitudinal motion is imparted to said stem.

5. In an engineer's valve, a valve member, a two part stem for said valve member, said stem being mounted in a journal and a lead ring disposed between the parts of said stem, said ring being adapted to be compressed transversely and expanded radially when longitudinal motion is imparted to said stem. 70

6. In an engineer's valve, a valve member, a journal, a two part valve stem extending from said valve member and mounted in said journal, the adjacent ends of said two parts being conical, and a ring fitting between said conical ends and being compressible so as to form a packing in the journal when longitudinal motion is imparted to said stem. 75

7. In an engineer's valve, a cylinder, a piston valve member operating in said cylinder, and an equalizing passage between the front and back of said cylinder, said equalizing passage becoming effective immediately upon the opening of said valve but being otherwise ineffective. 85

8. In an engineer's valve, a cylinder, having a peripheral opening leading into an air chamber, a valve operating in said cylinder, a secondary chamber at the end of said cylinder, said valve controlling the connection between said air chambers, said valve being disposed at rest in said cylinder in such position that there will be a leakage between said first-named chamber and the back of said valve through said peripheral opening. 90

9. In an engineer's valve, a cylinder having a peripheral opening leading into an air chamber, a valve operating in said cylinder, a secondary chamber at the end of said cylinder, said valve controlling the connection between said air chambers, said valve being disposed at rest in said cylinder in such position that there will be a leakage between said first-named chamber and the back of said valve through said peripheral opening, and an equalizing passage between the back 100 and front of said piston valve. 105

10. In an engineer's valve, a cylinder having a peripheral opening leading into an air chamber, a valve operating in said cylinder, a secondary chamber at the end of said cylinder, said valve controlling the connection between said air chambers, said valve being disposed at rest in said cylinder in such position that there will be a leakage between said first-named chamber and the back of 115 said valve through said peripheral opening, and an equalizing passage between the back and front of said piston valve, said equalizing passage being effective immediately upon the opening of said valve, but being otherwise ineffective. 120

11. In an engineer's valve, a casing having an action chamber, a pocket covering said casing, guides depending from said pocket into said casing, a channel piece re- 125

ciprocating in said guides, a stem mounted in said pocket, a pinion mounted on said stem engaging with teeth on said channel piece, a valve, and a stem extending from 5 said valve and arranged for engagement by said channel piece.

12. In an engineer's valve, a casing having an action chamber, a pocket covering said casing, guides depending from said 10 pocket into said casing, a channel piece reciprocating in said guides, a stem mounted in said pocket, a pinion mounted on said stem engaging with teeth on said channel piece, a valve, and a stem extending from 15 said valve and arranged for engagement by said channel piece, and a spring pressed pin in said spindle arranged for engagement in pockets in said channel piece to determine the stopping points.

20 13. In an engineer's valve, an air chamber, an action chamber, a valve controlling the

passage of air to and from said air chamber, a valve stem extending from said air chamber to said action chamber, said valve stem being in two parts, and means between the 25 parts of said valve stem for forming a packing in the stem journal when longitudinal motion is imparted to said stem.

14. In an engineer's valve, a valve member, a journal, a two part valve stem extending from said valve member and mounted in said journal, the adjacent ends of said 30 two parts being conical, and a compressible device between said conical ends arranged so as to form a packing in the journal when 35 longitudinal motion is imparted to said stem.

In witness whereof, I hereunto subscribe my name this 23rd day of July, 1910.

BURTON S. AIKMAN.
